OF NEW YORK, N. Y.

BOTTLE-CAP AND THE LIKE.

1,290,655.

Specification of Letters Patent.

Patented Jan. 7, 1919.

Application filed May 25, 1915. Serial No. 30,287.

To all whom it may concern:

Be it known that I, JONAS POPP, a citizen of the United States, and a resident of the borough of Brooklyn, county of Kings, city 5 and State of New York, have invented a certain new and useful Improvement in Bottle-Caps and the like, of which the following is a specification.

My invention relates to bottle caps and the 10 like of the kind which are employed to effect a tight seal upon bottles or other receptacles and which usually include a packing for effecting an air-tight closure. My improvement has for its object the provision 15 of a cap of this type which may be easily constructed and readily applied and which in its operative position on the bottle or other receptacle exerts a resilient tension.

By the use of such a cap in cases where 20 the resiliency is sufficiently strong a closure of great efficiency is secured owing to the fact that the packing is maintained in a properly compressed condition even though said packing may not have possessed or may 25 have lost its original elasticity. This property of the cap makes it possible to dispense with the expensive and frequently objectionable packings of the cork type. My improvement will be fully described herein- 30 after and the features of novelty will be pointed out in the appended claim.

An example of my improvement is shown in the accompanying drawings in which Figure 1 is an exterior side view of my im- 35 proved cap; Fig. 2 is a cross-section thereof on the line 2—2 of Fig. 3; Fig. 3 is an inverted plan view; Fig. 4 illustrates the cap in section in its initial position on the bottle; Fig. 5 is a similar view showing the cap 40 fully connected with said bottle; and Fig. 6 is a side view of the bottle neck with the cap applied thereto.

As shown in the drawings the cap which is preferably constructed of a suitable metal 45 which should have inherently resilient properties, comprises a disk 10 from which depends a peripheral flange 11 terminating in a series of fingers 15 each provided with an outwardly projecting ridge or bead 12 pref- 50 erably formed by bending the metal upon itself. Below the ridge or bead 12 the fingers 15 preferably flare outwardly in the initial condition of the cap as shown at 13, a curved surface being in this manner pro- 55 vided which in combination with a shoulder

on the receptacle to which the cap is applied exerts a resilient clamping action whereby said cap is firmly seated upon the mouth of said receptacle as is more fully explained hereinafter. The said fingers are separated 60 by recesses or cuts 14 which extend from the free edge of the flange to a point approximately just above the ridge or bead 12 as shown in Figs. 1 and 2. These recesses or cuts 14 preferably taper toward the said ridge or bead 12 and are located at spaced intervals throughout the circumference of the flange 11 whereby the fingers 15 are formed at the free edge of said flange as 65 illustrated in Figs. 1 and 2. The packing is 70 indicated by the numeral 17 and may be either a ring or other suitable or convenient form.

In applying the cap to a bottle such as 16 the cap with its packing is first placed upon 75 the mouth thereof. The positioning of the cap and packing on the bottle may be accomplished manually or by means of suitable mechanism as desired and this positioning may be accomplished by the plunger 80 hereinafter referred to. The cap in its first applied position is shown in Fig. 4. After having been brought into proper relation with the bottle the combined bottle, cap and packing are brought into operative relation 85 with a plunger 19 or the like which is suitably operated, preferably in a vertical direction, although the plunger may be stationary and the bottle moved into it. This plunger 19 preferably surrounds the flange 90 95 11 and is adapted to exert a downward pressure on the ridge or bead 12 which in consequence is bent downwardly on the line *a* as a pivot thus causing the fingers 15 to project beneath and bringing the curved surfaces thereof into contact with the bead or annular shoulder 20 of the bottle neck 18. A continued pressure or downward motion of the plunger 19 will finally straighten out 100 the upper half of said bead or ridge 12 and cause the free ends of said fingers 15 or more specifically the curved surfaces thereof to move inwardly along the bead 20 of the bottle neck 18 whereby the angle *b* is opened. 105 The cap finally assumes the position illustrated in Fig. 5. As the fingers 15 move along the bead 20 and the angle *b* is opened as described and the curved surfaces of said fingers in combination with the shoulder 110 exert a clamping action whereby the disk

10 is drawn toward the packing 17 which as a result is compressed between said disk and the neck 18 while the cap structure as a whole is at the same time placed under a 5 continuing resilient tension. In addition to this, by constructing the fingers with curved surfaces as described, the said fingers ride freely inward upon the shoulder 20 regardless of any surface inequalities which may 10 be present thereon, thus facilitating the application of the cap to the receptacle. In its final position on the bottle, the said cap is therefore locked thereon under said resilient tension and thereafter continues to exert 15 such tension whereby the packing 17 is maintained in a properly compressed condition even though said packing itself may initially not have been elastic or have lost its original elasticity. The present arrangement 20 thus permits the use of a packing material of any kind such as for instance paraffin paper and the like and does away with the necessity for using expensive cork or other elastic packings which are now necessary 25 and at the same time provides a seal having a maximum of efficiency and merit and of extreme simplicity. In other words after the cap has been secured upon the bottle, the latter is hermetically sealed by 30 the packing against the entrance of air or moisture and against the egress of any of the contents whereby said contents are effectively protected against injury or deterioration for an indefinite time. The cap 35 may be readily removed in any suitable manner as by means of well known implements such as are adapted for removing caps of the present type. The cap is so constructed and proportioned that the angle β 40 in the final position of the cap on the bottle will be located below and at a distance from the bead 20 thus providing an efficient purchase for such implements.

It will, of course, be understood that my 45 improvement is equally well adapted for use

in combination with jars or other receptacles as well as with bottles as illustrated.

Various changes in the specific form shown and described may be made within the scope of the claim without departing 50 from the spirit of my invention.

I claim:

The combination of a receptacle, a shoulder thereon extending at substantially right angles to the major axis of said receptacle, 55 a closure comprising a sealing disk, a packing between said sealing disk and the open end of said receptacle, a continuous peripheral flange depending from said disk and surrounding said receptacle, an outwardly 60 extending circumferential bead carried by said flange at its lower edge and formed by bending the closure material upon itself, said bead being located above said shoulder when the closure is initially placed in 65 position upon said receptacle, and a series of independent gripping fingers, inwardly curved in the normal positions and normally depending from said bead, said fingers having no portion extending upwardly beyond the bead, the latter being straightened out and pivotally moved on the lower edge of the peripheral flange whereby 70 said gripping fingers are caused to project in directions at substantially right angles to 75 said flange and shifted in their entirety beneath and into contact with said annular shoulder, the latter being tangential to the curves of said fingers whereby said closure is secured in operative position and said 80 packing is compressed beneath the disk and receptacle under a continuing resilient tension.

In testimony whereof I have hereunto set my hand in the presence of two subscribing 85 witnesses.

JONAS POPP.
